UNITED STATES PATENT OFFICE.

FRANK F. LEGGIE, OF CHICAGO, ILLINOIS.

WEED-DESTROYER.

1,177,424.

Specification of Letters Patent.

Patented Mar. 28, 1916.

Application filed December 10, 1915. Serial No. 66,171.

To all whom it may concern:

Be it known that I, FRANK F. LEGGIE, a citizen of the United States, residing at Chicago, in the county of Cook and State of Illinois, have invented new and useful Improvements in Weed-Destroyers, of which the following is a specification.

This invention relates to devices for destroying weeds by burning the same, and its 10 object is to provide a device of this kind which can be easily handled and controlled, and which is simple in construction and highly efficient in operation.

The object stated is attained by means of 15 a novel combination and arrangement of parts to be hereinafter described, and in order that the same may be better understood, reference is had to the accompanying drawings, forming a part of this specification.

In the drawings, Figure 1 is an elevation of the device; Fig. 2 is a plan view thereof, partly broken away; Fig. 3 is a vertical section on the line 2—2 of Fig. 2, and Fig. 4 25 is a cross-section on the line 3—3 of Fig. 3.

In carrying out the invention there is provided a liquid fuel burner mounted on wheels and positioned so that the flame is directed downward toward the ground to 30 burn the weeds or other growths to be destroyed. The burner is an elongated horizontal pipe 10 having perforations 11 and mounted in a sheet metal hood which is open at the bottom and supported at its ends on 35 wheels 12. The hood comprises a front wall 13, a rear wall 14 and end walls 15. The wheels 12 are mounted on the end walls of the hood, and to said walls are also fixed the branches 16 of a fork or yoke carrying a 40 handle 17 whereby the device is propelled over the ground.

The top of the hood has a contracted portion 18 formed by a wall 19 extending downward from the top of the front wall 13 in 45 spaced relation therewith and in the same direction. The rear wall 14 of the hood is connected to the wall 19 some distance above the bottom edge of the latter, and extends downward and rearward, or divergently 50 with respect to the wall 13. The wall 19 does not extend down as far as the walls 13 and 14 but terminates some distance from the bottom or mouth of the hood.

The burner pipe 10 is located in the contracted top portion of the hood and has one 55 end closed by a plug 20, its other end being

connected to a valve casing 21. Extending parallel to the burner pipe 10, a suitable distance below the same, is a pipe or tube 22 serving as a retort in which the gas or vapor 60 is generated. This underlying retort tube is connected at one end to the valve casing 21 by a lateral bend 23, and the other end has a lateral bend past the plug 20 and extends from the top of the hood through an aperture therein, to a fuel reservoir 24 carried by the handle 17.

The bottom edge of the wall 19 has an inward curl 25 forming a trough designed to hold a wick 26 of asbestos or other suitable 70 material. The retort tube 22 extends parallel to this trough, in proximity thereto. The valve in the casing 21 to which the burner pipe 10 and the retort tube 22 are connected has a handle 27 which extends from 75 the top of the hood so as to be readily accessible. In the wall 19, above the wall 14, are openings 28 to admit air to the burner.

The bottom edges of the walls 13 and 14 have outward curls 29 so that the hood may 80 readily pass over uneven ground.

The reservoir 24 is located at a higher level than the burner so that the fuel flows by gravity to the burner when the valve in the casing 21 is opened. Upon opening this 85 valve slightly, the liquid fuel issues from the perforations 11 and drops on the wick 26, which is then ignited. The proximity of the retort tube 22 to the wick quickly heats the liquid fuel in the latter and vaporizes the same. The vapor thus formed issues from the perforations 11 and burns with an intense flame, air to support combustion being drawn into the chamber 18 through the 90 openings 28. The sheet of flame beating against the wall 13 is deflected downward and past the retort tube 22 so that the vaporization of the fuel is continued. The heat and flame are deflected down on the ground, 95 quickly destroying the weeds and other growths. The size of the flame is readily controlled by turning the valve handle 27, the same being readily accessible. The weeds can therefore be completely destroyed or merely singed.

The device can be easily handled, it being pushed over the ground in the same manner as a lawn mower. It will also be apparent that the device is not limited to the destruction of weeds, but may, with equal facility, 110 be employed for melting snow and ice on sidewalks or streets.

I claim:—

The combination of a hood open at the bottom and mounted for travel over the ground, said hood having diverging front 5 and rear walls, and a wall connected to the top of the front wall and extending in spaced relation therewith and in the same direction to form a burner chamber at the top of the hood, the bottom of said last- 10 mentioned wall being above the bottom of the

hood and having a trough, and the rear wall of the hood extending from said last-mentioned wall above the trough, and said last-mentioned wall having air inlets above the rear wall of the hood, a liquid fuel burner in 15 the aforesaid chamber, and a retort connected to the burner and extending in proximity to the trough.

In testimony whereof I affix my signature.

FRANK F. LEGGIE.
